(57) **CLAIM**

The ornamental design for a “spray bottle,” as shown and described.

DESCRIPTION

FIG. 1 is a perspective view of a spray bottle showing my new design;

FIG. 2 is an enlarged scale, partial perspective view as in the upper portion of FIG. 1 but showing the nozzle portion in a closed position;

FIG. 3 is a front elevational view of FIG. 1;

FIG. 4 is a side elevational view thereof;

FIG. 5 is a rear elevational view thereof;

FIG. 6 is a top plan view according to an embodiment;

FIG. 7 is a bottom plan view according to an embodiment;

FIG. 8 is a perspective view showing a second embodiment of my new design for a spray bottle;

FIG. 9 is an enlarged scale, partial perspective view as in the upper portion of FIG. 8 but showing the nozzle portion in a closed position;

FIG. 10 is a front elevational view of FIG. 8

FIG. 11 is a side elevational view thereof;

FIG. 12 is a rear elevational view thereof;

FIG. 13 is a top plan view thereof; and,

FIG. 14 is a bottom plan view thereof.

The broken lines depict portions of the spray bottle that form no part of the claimed design.

1 Claim, 4 Drawing Sheets
